WAX APPLICATOR

Theodore Mungen, Philadelphia, Pa., assignor to
Edward G. Budd Manufacturing Co., Philadel-
phia, Pa., a corporation of Pennsylvania

Application October 12, 1933, Serial No. 693,246

2 Claims. (Cl. 15—231)

The present invention relates in general to applicators or swabs, and more particularly to an applicator or swab for applying wax to floors and the like.

5 The invention has as its main object the provision of an applicator of the above type which shall be light, sturdy, simple in construction and cheap to manufacture.

The main object of the invention is attained in 10 general by providing a light backing or holding member of wood or the like with a novel one-piece clamp member for clamping the pad material to the holder in a simple and effective manner, the clamp being capable of manufacture from a single small piece of stock sheet metal, such as scrap metal, so formed as to give maximum strength and lightness with simplicity of structure.

15 Other objects and advantages of the invention will be apparent from a perusal of the following specification and the drawing accompanying same.

In the drawing Fig. 1 is a perspective view of the finished applicator.

Fig. 2 is a section on the line 2—2 of Fig. 3.

20 Fig. 3 is a section on the line 3—3 of Fig. 2.

Fig. 4 is a perspective view of the sheet metal clamp member.

25 Fig. 5 is an enlarged fragmentary section on the line 5—5 of Fig. 2.

30 Referring to the drawing in detail, 1 is the back or holder, preferably of wood, having a flat rectangular base portion 2, and a pair of bores 3 and 4 extending through from the base to the top of the holder, substantially at right angles to the base. The applicator pad 5 is securely held in place on the base by a substantially flat sheet metal clamp member 6 held firmly in clamping relation with the holder 1 by up-standing lugs 7 and 8 which extend up into the bores 3 and 4 respectively, resting against one side of the bore and held securely in place by screws 9 and 10 wedged down into the bore between the side of the bore and the lug. The threads of the screws 9 and 10 are hardened so as to cut into the sheet metal lugs 7 and 8 respectively, as indicated in Fig. 5, where it will be seen that the screw 10 is wedged into the bore 4 so as to force the lug 8 against one side of the bore, the screw threads cutting into both the lug 8 and the opposite wall 45 of the bore.

50 The clamp member 6 is stamped from a single piece of sheet metal to form an oblong rectangular metal plate having 4 oblong openings 11, 12, 13 and 14 near each corner, so spaced and arranged as to form an oblong frame with integral

cross arms 15 and 16 extending through the center from side to side and end to end respectively.

The cross arms thus serve to brace the frame, which bracing effect is enhanced by having the arms increase in width toward their junction with the margin of the frame, as clearly shown in Fig. 4. Serrated clamping edges 17 are struck up along the outer edges of each of the openings 11, 12, etc., substantially parallel to the adjacent one of said edges 18 of the clamping member and spaced inwardly therefrom as shown in Figs. 3 and 4. Serrated clamping edges 19 are also struck up along the end edges 20 of the clamp. The holding lugs 7 and 8 are also integral and are struck up from the body material of the cross arm 16 and so formed as to project upwardly, each from a point on the longitudinal axis of the plate on opposite sides of the center of the plate, but closer to the adjacent end of the plate than to the center. This arrangement positions the lugs midway between a pair of opposed parallel clamping edges 17, but offset longitudinally toward an adjacent clamping edge 19, thus effecting a substantially even distribution of pressure along the serrated clamping edges when the lugs are secured in clamping relation with the holder 1.

55 It will be clear from Fig. 4 that the cutting out of the holes 11, 12, etc., materially lightens the plate without weakening it as a rigid clamp, due to the fact that the side and end margins of the clamp frame thus formed are reinforced midway by the widening junction between the cross arms and the margin of the frame, the frame being further reinforced by the struck up clamping edges 17 and 19. The clamp 6 is of greater width than the base portion 2 of the holder so as to project both sides thereof, while the serrated clamping edges 17 are spaced in sufficiently to underlie the base 2, so that the floor pad 5 will be securely clamped between clamp 6 and base 2 and at the same time extend well out in advance of the side edges of the base and holder, as shown in Figs. 1 and 3. This extension of the pad will then act as a buffer to prevent marring of side trim or wash boards. As shown in Fig. 2 the clamp is made slightly shorter than the base of the holder so as to underlie the ends of the holder permitting the clamping edges 19 to clamp the ends of the pad against the base.

50 In applying the pad to the holder it is first wrapped around the clamp 6 as indicated in Fig. 3 and the clamp placed in position as shown, with the holding lugs extending into the bores

in the holder and resting against one side of the bore. The holder 1 is now pressed down firmly on to the clamp so as to clamp the upper lapped-over portions of the pad firmly between the 5 clamp and the holder while the screws 9 and 10 are placed in position and screwed down into the bores between the side of the bore and the lug, the hardened threads of the screw cutting grooves in the lug to hold the parts in this 10 clamped position, after which the downward pressure on the holder may be released.

After the parts are thus assembled with the pad held firmly between the clamp and holder, the clamp may be further tightened by further 15 turning the screws after their heads have engaged with the top of the holder, which will cause the lugs to be drawn up by coaction of the screw thread with the grooves cut in the lugs.

While I have herein shown and described a 20 preferred embodiment of the invention for the sake of disclosure it is to be understood that the invention is not limited to such embodiment, but contemplates all such variations and modifications thereof as fall fairly within the scope of 25 the appended claims.

What I claim is:

1. A sheet metal clamp for applicator comprising a main body of sheet metal having a perimeter substantially smooth in edges, and pad biting serrations integral with said body projected at right angles from the upper side of said body, marginally inwardly removed from said substantially smooth edges. 5

2. An applicator comprising a base and a co-acting pad clamp, the latter comprised of sheet metal having a perimeter of substantially unbroken lines, pad biting serrations integral with said clamp and projected at right angles from the upper surface thereof, within the perimeter of the clamp and within the perimeter of the 15 base, whereby they bite down on the pad between the clamp and the base, and the pad may be folded smoothly around the unbroken clamp perimeter, and also a pair of integral tongues of sheet metal projected at right angles from 20 the upper surface of said clamp and entering the body of said base whereby to secure the clamp to the base. 25
